DESK PAD

Samuel N. Hope, Wauwatosa, Wis., assignor to
Columbian Art Works, Milwaukee, Wis., a cor-
poration of Wisconsin

Application July 2, 1937, Serial No. 151,649

5 Claims. (Cl. 281—1)

The invention relates to desk pads such as calendar pads and the like, and more particularly to cover means for the pads.

An object of the invention is to provide a simple, 5 neat and inexpensive cover for a desk pad, the cover when in closed position serving to prevent blowing and curling of the pad sheets and to conceal written matter on the pad, while exposing calendar or other indicia on the pad, and the cover when in open position forming a screen to obscure writing on the pad from nearby persons.

Another object of the invention is to provide a desk pad cover having an improved and simplified hinge connection which extends below the 15 plane of the top surface of the pad.

A further object is to provide a desk pad in which the cover and its mounting are adapted to overlap or embrace the base of the pad after sheets are removed from the pad.

20 The invention further consists in the several features hereinafter described and claimed.

In the accompanying drawing, illustrating an embodiment of the invention,

Fig. 1 is a top plan view of a desk pad constructed in accordance with the invention, the cover being in closed position;

Fig. 2 is a side elevation of the pad, the open position of the cover being indicated in dotted lines;

30 Fig. 3 is a detail sectional view taken along the line 3—3 of Fig. 2, but showing the cover in open position, and

Fig. 4 is a detail sectional view taken along the line 4—4 of Fig. 1, some of the pad sheets having been removed.

In the drawing, 10 designates a pad base of any suitable construction, here shown to be of sheet metal and to have a sloping top, the front or foot portion of the base having a centrally notched 40 pencil trough 11 with rounded embossments 12 to rest on a desk or other support, and the rear or head portion of the base having rubber tips 13 to rest on the desk. The base supports thereon a stack of paper sheets 14 which are secured 45 thereto in any suitable manner, as by a pair of headed posts 15 which pass through apertures in the sheets and are screw-threaded through the base.

50 A flat head plate or binding plate 16 rests on the top sheet of the stack, the plate preferably being of sheet metal and having downturned side flanges 17 and a downturned rear flange 18 which project below the plane of the pad top. The head plate 16 is here shown to be detachably secured 55 to the base by the headed screw posts 15.

A rigid cover 19, preferably in the form of a flat sheet metal plate, rests on the top surface of the pad and has downturned side flanges 20 which project below the plane of the pad top. The rear ends of the flanges 20 are extended to form ears 21 which bear on embossments 22 formed on the head plate side flanges 17 and are pivotally secured thereto by axially aligned rivets 23, so that the cover may be swung about a substantially horizontal axis. The rear edge of the cover has a wide notch 24 which exposes calendar indicia 25 printed on the pad sheets near the head plate 16, the side portions of the cover adjacent the notch forming arms of angular cross-section.

At its front edge the cover is provided with a 15 curved lifting lip 26 for raising the cover to its open position, shown by dotted lines in Fig. 2 and by full lines in Fig. 3. When open, the cover stands in a substantially upright position with the rear edge thereof engaging embossments or 20 ridges 27 formed on the top of the head plate 16 near its opposite side edges. If desired, the inner face of the cover and other parts may bear suitable advertising indicia, not shown.

The cover when closed extends substantially to 25 the free ends of the sheets and prevents the sheets from blowing about and from curling. The cover also conceals any memoranda or notations which may be made on the sheets. The notch 24 in the closed cover, however, exposes the calendar in- 30 dicia 25 which are printed on the sheets near the head plate 16, so that it is not necessary to raise the cover to refer to this indicia. When the cover is closed the flat top portions of the head plate and cover lie in substantially the same 35 plane and extend only slightly above the uppermost sheet.

When it is desired to make notations on the sheets or to tear out sheets, the cover is raised by its lip 26, or by a side edge, to the upright 40 open position seen in Fig. 3, in which it will remain, being slightly over center. The upright open cover forms a screen to obscure the notations from persons who may be sitting or standing opposite the writer.

It may be desirable to occasionally remove the stubs of the torn-out sheets, and this can be done after removing the screw posts 15 and plate 16 with its attached cover 19. Upon replacing the plate 16 and screw posts on the pad, the downturned flanges of the plate and cover will overlap or embrace the base, as indicated in Fig. 4, after the pad is sufficiently reduced in thickness, thereby permitting the pad to be thinned down to the last sheet.

45

50

55

The construction of the device permits the cover and its pivotal mounting to be inexpensively manufactured, and provides for display of the calendar indicia in its preferred location above the writing space of the sheets.

5 5 What I claim as new and desire to secure by Letters Patent is:

1. In a desk pad having a base adapted to support thereon a stack of sheets, the combination of 10 a head plate engageable with said stack of sheets and secured to said base, and a cover for said sheets having downwardly projecting side flanges pivotally connected to said head plate, said cover having a transverse edge adjacent said head plate and engageable with said head plate to limit the upward swinging movement of said cover to a substantially upstanding position.

2. In a desk pad having a base adapted to support thereon a stack of sheets, the combination of 20 a head plate adapted to bear on said stack and secured to said base, and a cover plate normally resting on said stack, each plate having downturned side flanges integrally formed thereon and overlapping the sides of said stack, said cover plate side flanges being pivotally connected to said head plate side flanges at an axis below the top plane of said stack for swingably mounting said cover plate.

3. In a desk pad having a base adapted to support thereon a stack of sheets, the combination of 30 a substantially flat head plate adapted to bear on said stack and secured to said base and having downturned side flanges overlapping said

stack, and a substantially flat cover plate normally resting on said stack and having downturned side flanges pivotally connected to said head plate flanges at an axis below the top plane of said stack for swingably mounting said cover, 5 said cover plate when closed lying substantially in the plane of said head plate.

4. In a desk pad, the combination of a base adapted to support thereon a stack of removable sheets, means for securing said stack of sheets 10 to said base including a head plate adapted to rest on said stack and to descend with the stack when the stack is thinned, and a cover for said stack of sheets adapted to normally rest on said stack and having downwardly projecting side 15 flanges pivotally connected to said head plate and adapted to overlap the sides of said stack, said flanges being farther apart than the width of the upper portion of said base and overlapping said base when the stack is thinned.

20 5. In a desk pad, the combination of a base adapted to support a stack of removable sheets with indicia thereon, means for securing said sheets to said base including a head plate adapted to rest on said stack and to descend with the 25 stack when the stack is thinned, and a cover for said sheets adapted to normally rest on said stack and having downwardly projecting side flanges overlapping the sides of said stack and pivotally connected to said head plate, said cover 30 having a notch adjacent said head plate to expose the sheet indicia when the cover is closed.

SAMUEL N. HOPE.
